APRON CONTROL FOR CARRYING
SCRAPERS

Julian D. Rapp, Turlock, Calif.

Application May 31, 1938, Serial No. 210,878

10 Claims. (Cl. 37—118)

This invention relates to a carrying scraper and particularly to an apron for the front end of the same such as is commonly used to aid in loading the bowl while scraping and also to form 5 a dirt retaining closure for the front end of the bowl when the load is being transported.

The principal object of my invention is to provide what I believe to be a novel arrangement 10 for mounting and controlling the movement of the apron so that at the option of the operator, the apron may be reciprocated lengthwise of the bowl so as to recurringly drag dirt back into the bowl either while scraping, or while discharging if the bowl is of the rear dump type. Also apron 15 guiding means is provided which is so arranged that the apron when returning to a point ahead of the incoming dirt, will not tend to interfere with the natural movement of such dirt into the bowl.

20 A further object is to mount the apron and control mechanism entirely on the bowl of the scraper, except for a single pull cable which extends forwardly to the tractor for operation. By so doing, it is immaterial, as far as the mounting and operation of the apron is concerned, how 25 the bowl itself is mounted for movement between scraping and dumping positions, whether the bowl dumps from the front or rear end, or how such dumping is effected.

30 A further object of the invention is to produce a simple and inexpensive device and yet one which will be exceedingly effective for the purpose for which it is designed.

These objects I accomplish by means of such 35 structure and relative arrangement of parts as will fully appear by a perusal of the following specification and claims.

In the drawings similar characters of reference 40 indicate corresponding parts in the several views:

Figure 1 is a sectional elevation of my improved apron mounting and control mechanism as disposed in a scraper bowl, and showing the position of the apron as moving forward and down to a point ahead of the incoming dirt.

45 Figure 2 is a similar view showing the apron as moving upwardly and rearwardly.

Figure 3 is a similar view showing the apron in a closure forming position.

50 Figure 4 is a fragmentary top plan view of the structure.

Referring now more particularly to the characters of reference in the drawings, the scraper bowl in which the apron is mounted comprises side plates 1 and a bottom plate 2 terminating in 55 a sloping blade 3 disposed some distance back

of the front and of the side plates. Since as above stated, the particular type and mounting of the bowl has no bearing on the present invention and does not affect its operation, I deem it unnecessary to show any such particular type 5 of bowl or scraper as a whole.

The front apron comprises a plate 4 having a slight downward slope or curvature to the rear, and which extends nearly the full distance between the side plates 1. The apron plate is provided with side wings 5. The apron is rigidly connected to and depends from longitudinally extending side beams or arms 6 which slidably project through guide and supporting sleeves 7. These are rockably mounted on a cross shaft 8 15 supported from the bowl adjacent the top thereof and well toward its rear end. Rollers 9 are preferably mounted on the sleeves to engage the sides of the arms and reduce any tendency of lateral binding. 20

Supported from the apron in front and at the sides thereof intermediate its top and bottom are rollers 10. These are spaced to fit between the side plates 1 and are adapted to ride on track sections mounted on said plates inside the bowl. One such track section comprises upwardly and rearwardly sloping rails 11 having their inception at the lower edge of plates 1 some 25 distance ahead of blade 3, and extending to the top of said plates. Said rails are then bent to extend rearwardly along the top of the side plates as far as the sleeves 7. 30

Another track section comprises rails 12 extending forwardly along the top of plates 1 from a point in front of the rails 11 a greater distance 35 than the diameter of rollers 10, said rails 12 being then bent down with a forward slope to a termination well clear of the ground. The gap formed between each pair of rails 11 and 12 is normally bridged by a switch rail 13 hinged 40 on the rail 12 for upward opening movement and closing down of itself against rail 11.

A third track section comprises rails 14 substantially horizontal though having a slight 45 upward slope to the rear. These are disposed ahead of the sloping portion of rails 11 and below rails 12 some distance, being spaced from rails 11 a distance greater than the diameter of rollers 10. The gap between corresponding rails is closed by an upwardly opening switch rail 15 50 hinged on rail 14 and also closing of itself against rail 11. The rails 14 at their forward end terminate in front of blade 3 and at a distance from the ground greater than the depth of the apron from the rollers to its lower edge. 55

In operation, it will be seen that if the rollers 10 drop off the front end of either the rails 12 or 14, the apron will then fall of its own weight to the ground, the supporting sleeves 7 rocking 5 on the shaft 8. The apron will then occupy a position some distance in front of the scraper blade as indicated in dotted lines in Fig. 1. Rearward movement of the apron from that position until it contacts the scraper blade as shown in 10 Fig. 3 and as induced by a pull on the arms 6, may take place without any restriction against movement either up or down as the ground contour may determine. This is because the rollers during this movement are not engaged with any 15 rails and their vertical or longitudinal movement is therefore not limited to any definite path.

When the apron engages the scraper blade in closure forming position, however, the rollers 10 then engage the adjacent lower portion of the 20 rails 11 on their forward faces, and a further rearward pull on the arms 6 causes the apron to both lift and move rearwardly as the rollers follow said rails. As the rollers engage the switch rails 15 from underneath, they lift the 25 same as shown in Fig. 2, and continue up without interference. The same is true when the rollers reach and engage the upper switch rails 13, said switch rails yielding to allow the rollers to move along the upper horizontal portion of the rails 30 11 as indicated in Fig. 2.

In this manner the dirt is engaged at the scraper blade or from ahead of the same, and is both raised and moved rearwardly in the bowl. The dirt is thus positively shoveled into or toward 35 the rear portion of the bowl and the front end of the same is relieved of a corresponding portion of the load and scraping and loading is made easier. While the rails 11 guide the apron against downward movement while being raised, 40 they do not prevent direct upward movement of the apron if necessary for the same to yield upwardly somewhat as it is being pulled back against a mass of dirt.

When it is desired to return the apron to its 45 initial forward position after being advanced, it will be seen that the apron cannot move through the same path (the sloping portion of rails 11) and contact the dirt in the bowl on account of the closed switches. The rollers are therefore 50 shunted onto the rails 12, which maintain the apron raised until it is well clear of the ground and dirt and until said apron drops off the rails in front of the dirt being scraped up. The intermediate rails 14 are for the purpose of allowing 55 the apron to be reciprocated through a shorter endless path of movement if desired, and also enables the apron to be held in a definite position above and in front of the scraper blade, as indicated in dotted lines in Fig. 3.

60 The apron is moved on its rearward or working stroke by a single pull cable 16. This extends from a power drum on the tractor to which the scraper is connected to one pulley of a sheave block 17 mounted on one of the sleeves 7. The cable then extends forwardly and about a pulley 18 mounted on top of the apron on the adjacent side and then back to and about the other pulley of the block 17. The cable then preferably extends by means of direction changing pulleys 19 to and about pulleys 20 and 21 on the other sleeve 7 and the apron on the opposite side respectively, to a final dead end on the apron as shown in Fig. 4. The point of direct pull from the tractor being taken at the supporting sleeve, such pulling 75 does not tend to exert any actual lifting action

on the apron which would affect or interfere with its movement along the rails or with its otherwise unrestricted vertical movement; the normal over-balancing weight of the apron tending to hold the same down and engaged with the rails. 5 Movement of the apron on its return or idle stroke is preferably imparted thereto by suitable spring means applied to the arms 6. This may be done in various ways. In the present instance, I have shown spiral springs 22 mounted 10 in connection with and inside cable drums 23 mounted on the outside of the bowl near the front. Separate cables 24 wound on these drums extend rearwardly and are attached to the arms 6 rearwardly of the sleeves as shown at 25 in 15 Fig. 4. The springs are applied to the drums and the cables are wound on the latter in such a manner that rotation of the drums as induced by the springs tends to wind the cables thereon. As the apron and its mounting arms are moved 20 rearwardly and the cables are payed out from the drums, the springs become wound up, so that they have ample strength to pull the apron forwardly through its entire stroke.

From the foregoing description it will be readily seen that I have produced such a device as substantially fulfills the objects of the invention as set forth herein.

While this specification sets forth in detail the present and preferred construction of the device, 30 still in practice such deviations from such detail may be resorted to as do not form a departure from the spirit of the invention, as defined by the appended claims.

Having thus described my invention, what I 35 claim as new and useful and desire to secure by Letters Patent is:

1. In a scraper, a bowl having side plates, a front apron movable between the plates, means mounting the apron for movement both lengthwise and vertically of the bowl, means to pull the apron rearwardly and means to move the apron forwardly; said apron mounting means comprising an arm rigid with and projecting rearwardly from the apron, and a sleeve mounted on the 45 bowl for rocking movement in a vertical plane and through which the arm slidably projects, and said apron pulling means including a pull cable extending rearwardly from a point of pull ahead of the bowl, a pulley on the sleeve about 50 which the cable passes and then extends forwardly and a connection between the apron and said forwardly extending portion of the cable.

2. In a scraper, a bowl having side plates and a scraping blade between the plates rearwardly of the front end thereof, a front apron disposed between the plates, means mounting the apron for movement both lengthwise and vertically of the bowl, means to pull the apron rearwardly, means to move the apron forwardly, rails on the 60 plates on the inside extending upwardly and rearwardly from adjacent the level of and in front of the blade, and elements on the apron to engage the forward face of the rails.

3. A structure as in claim 2 in which the elements and rails are arranged relative to the blade so that the apron may engage the blade in closing relationship after rearward movement of the apron from a ground engaging position ahead of the blade. 70

4. A structure as in claim 2, with other element supporting rails on the plates extending forwardly from in front of the first named rails and terminating at their forward end at a level above and in front of the lower termination of the first 75

- named rails and at a height above the bottom of the bowl greater than the depth of the apron below the elements, the rear end of said other rails being spaced from the first named rails a distance sufficient to allow the elements to pass therebetween, and upwardly movable switch rails hinged at the rear end of said other rails and extending rearwardly to normally close the gap between the rails. 5
- 10 5. A structure as in claim 2, with other element supporting rails arranged to deflect the apron when moving forwardly after being raised a predetermined distance and cause the same to return to a ground engaging position along a path initially above and extending to a point in front of the first named rails. 10
- 15 6. In a scraper, a bowl having side plates and a scraping blade between the plates rearwardly of the front end thereof, a front apron disposed between the plates, arms rigid with and projecting rearwardly from the top of the apron, sleeves mounted on the bowl at the top and rearwardly of the blade for rocking movement in a vertical plane and in which the arms are slidably supported means applied to the apron to pull the same rearwardly without interfering with rocking of the sleeves and arms, means to move the apron forwardly, rollers on and projecting from the sides of the apron, roller supporting rails extending forwardly along the side plates ahead of the sleeve and adjacent the top of the plates 15 and then sloping down to a termination adjacent the level of and in front of the blade, other rails extending forwardly from in front of the upper portion of the first named rails to a termination in front of and on a level higher than the lower 20 termination of said first named rails, said other rails at their rear end being spaced from the first named rails a distance greater than the diameter of the rollers and upwardly opening switch rails extending rearwardly from said other rails and normally closing the space between the separated rails. 20
- 25 8. A structure as in claim 7, with additional roller supporting rails extending forwardly in spaced relation to the sloping portion of the first 25 named rails below said other rails, and upwardly opening switch rails extending rearwardly from the additional rails and normally closing the space between said additional and first named rails. 30
- 30 9. A structure as in claim 2, in which said means to move the apron forwardly comprises a spring, and means between the apron and spring to place the latter under increasing tension with the rearward movement of the apron. 35
- 35 10. A structure as in claim 6, in which said means to move the apron forwardly comprises a pair of cable drums turnably mounted on the bowl ahead of the sleeves, cables wound on the drums and extending rearwardly to connections 40 with the arms rearwardly of the sleeves, and springs acting on the drums to rotate the same in a cable winding direction. 40
- 40 45
